UNITED STATES PATENT OFFICE.

EARL HENRY BEKKERING, OF DULUTH, MINNESOTA, ASSIGNOR TO THE DULUTH SHOW CASE COMPANY, OF DULUTH, MINNESOTA, A CORPORATION OF MINNESOTA.

SHELF-BOX.

1,074,344.

Specification of Letters Patent. Patented Sept. 30, 1913.

Application filed August 3, 1912. Serial No. 713,110.

To all whom it may concern:

Be it known that I, EARL HENRY BEKKERING, a citizen of the United States, residing at Duluth, in the county of St. Louis and State of Minnesota, have invented certain new and useful Improvements in Shelf-Boxes, of which the following is a specification.

My invention relates in general to shelf boxes, and more particularly to boxes of this type which are designed to contain heavy articles such as hardware and the like, although it will be apparent that the invention has a much wider application, being capable of efficient embodiment in shelf boxes of various types and numerous other receptacles constructed for various purposes.

One of the principal objects of my invention is to provide a shelf box which while being of exceptionally strong construction will be light in weight, cheap to manufacture and pleasing in appearance.

A further object of my invention is to provide a shelf box wherein the walls will be efficiently held together without the use of nails, brads, screws or the like, which may in time become loosened and displaced, and also without the use of glue or other adhesive which may be affected by the temperature and moisture of the air.

A still further object of the invention is to provide a shelf box wherein the danger of shrinkage and expansion of the walls forming the same will be reduced to a minimum.

Further objects and advantages of my invention will be apparent as it is better understood from the following description which, taken in connection with the accompanying drawing, discloses one preferred embodiment thereof.

On the drawing: Figure 1 is a perspective view of a shelf box made in pursuance of my invention; Fig. 2 is a plan view of the same; Fig. 3 is a vertical sectional view taken on the line 3-3 of Fig. 2 showing the means of securing the walls of the box together, and Fig. 4 is a transverse vertical sectional view taken on the line 4-4 of Fig. 2.

In the embodiment of my invention shown on the drawing and hereinafter described, the shelf box is formed primarily of two end members 10 and 11 of wood or other

suitable material and a sheet of suitable metallic material 12 which forms the intermediate walls connecting the end walls. Each of the end walls 10 and 11 is provided with a transversely disposed slot or groove 13 formed in each outer vertical end face thereof. The metallic sheet 12 is bent substantially at right angles to itself along two parallel longitudinally extending lines to form the bottom wall 14 and the side walls 15 and 16. The material at the end edges 17 and 18 of the bottom wall is cut away a substantial distance to provide outwardly extending edges at each end of the vertical side walls. These edges are bent inwardly of the side walls as at 19 and 20 and folded back upon themselves to provide folds 21 which are adapted to be inserted in their corresponding slots 13 formed in the vertical edges of the end walls. After the folds 21 have been disposed in the slots or grooves 13 a pin 19 is driven downwardly within each fold. It is frequently advisable to provide an enlargement 20 at the base of the slot as is shown in Fig. 3 by boring a small round hole in the end wall to slightly greater depth than the length of the pin 19, the rest of the slot being formed by making a saw cut in the edge of the end wall communicating with the round hole formed as described. It is apparent that where the ends are made of soft material that the circular hole may be omitted and the pins used not only to expand the metal of the fold but also the material of the ends about the folds as the folds are expanded.

In Fig. 3 a comparatively short pin is shown, as I believe the box is given greater strength by its use than were a longer one employed, as the material of the end wall beneath the end of the short pin aids in preventing the fold from sliding longitudinally in the groove. This pin extends between and expands only a portion of the fold. The end edges 21 of the bottom are disposed beneath the ends 10 and 11, and extend substantially to the lower ends of the grooves or slots 13, preventing thereby any elasticity or resiliency of the sheet from tending to withdraw the bottom portions of the folds from the grooves or slots 13. The sheet 12 forming the walls 14, 15 and 16 is further held in position by bending inwardly its upper edges 22 over the tops of

the end walls 10 and 11. These edges are preferably folded back upon themselves as at 23 before they are bent down to engage the tops of the end walls to prevent buckling 5 of the side walls and to provide smooth rigid upper edges on the side walls of sufficient strength and evenness to permit the shelf boxes to be piled one upon the other and to permit one of them to slide easily 10 between the ones immediately above and below without damage to the boxes.

Upon the front end 10 I provide a handle 24 of any suitable type and a card-receiving member or label-holder 25, it being obvious, 15 however, that this member may be omitted and one of the articles contained in the box secured in its place, as is the custom in many hardware stores. One of the metallic sides 16 is provided with a depressed area 26 20 which is preferably covered with enamel upon which marks setting forth the cost, selling price and other information may be made and readily changed without injuring the enamel.

25 It will be apparent that various changes may be made in the form, construction and arrangement of parts without departing from the spirit and scope of my invention, or sacrificing any of its advantages, the 30 form hereinbefore disclosed being merely one preferred embodiment thereof.

I claim:—

1. A shelf box having side and end walls, one of said walls having a transversely extending groove at its end and a wall adjacent the said end having its edge folded upon itself and disposed in the said groove, and means for spreading the said fold after the edge is in position within the groove to 40 secure the walls together.

2. A shelf box having side and end walls, one of said walls having a transversely extending groove at its end and a second wall having an edge adjacent the said end of the 45 first-mentioned wall disposed in said groove, and means expanding the edge of the second-mentioned wall after it has been positioned in the groove at the end of the first-mentioned wall.

50 3. A shelf box having side and end walls, one of said walls having a transversely extending slot at its end, said slot having a reduced transverse dimension at its outer edge, a second wall having the edge adjacent the said end of the first-mentioned wall disposed in the said slot, and means for expanding the edge of the second-mentioned wall after the same has been disposed in the 55 said slot.

60 4. A shelf box comprising side and end walls, one of said walls having a transversely disposed groove in its end, and a second wall having the edge adjacent the said end bent from the plane of the said wall and folded upon itself and inserted in the 65

said groove, and means disposed in the fold of the said edge for expanding the same to retain the wall in position.

5. A shelf box having two opposite walls provided with a transversely disposed groove at each end, a plurality of intermediate walls formed of a single sheet of suitable material bent to embrace the said opposite walls and having the edges thereof adjacent the said grooves bent to dispose the same in the said grooves, and means for expanding the said edges within the grooves to permanently secure the said opposite walls to the bent sheet forming the intermediate walls. 70 75

6. A shelf box having two opposite walls provided with a transversely disposed groove at each end, a plurality of intermediate walls formed of a single sheet of suitable material bent to embrace the said opposite walls and having the edges thereof adjacent the said grooves bent to dispose the same in the said grooves, and means for expanding the upper portion of the said edges disposed within the grooves to permanently 90 95 secure the said opposite walls to the bent sheet forming the intermediate walls. 90

7. A shelf box having two opposite walls provided with a transversely disposed groove at each end, a plurality of intermediate walls formed of a single sheet of suitable material bent to embrace the said opposite walls and having the edges thereof adjacent the said grooves bent to dispose the same in the said grooves, the edges of the 100 said sheet being bent inwardly of the construction, and means for expanding the said edges within the grooves to permanently secure the said opposite walls to the bent sheet forming the intermediate walls. 105

8. A shelf box having two opposite walls provided with a transversely disposed groove at each end, a plurality of intermediate walls formed of a single sheet of suitable material bent to embrace the said opposite 110 walls and having the edges thereof adjacent the said grooves bent to dispose the same in the said grooves, the edges of the said sheet being bent inwardly of the construction and folded back upon themselves, and means for 115 expanding the said edges within the grooves to permanently secure the said opposite walls to the bent sheet forming the intermediate walls.

9. A shelf box comprising a pair of opposite walls each having a transversely disposed groove at each end thereof, intermediate walls connecting the said walls formed of a single sheet of suitable material bent to embrace three edges of the said opposite 120 walls, the edges of the said sheet adjacent the said grooves being folded upon themselves and bent to dispose the same within the grooves, and a pin disposed in the upper portion of each fold to expand the same to se- 125 130

cure the opposite walls to the sheet of material forming the intermediate walls.

10. A shelf box having side and end walls, one of said end walls having a groove extending transversely thereacross between opposite edges and the wall adjacent said end wall being folded upon itself and disposed in said groove, and an element inserted in

the fold within the groove spreading the same into firm contact with the walls of the 10 groove and serving to permanently lock said walls together.

EARL HENRY BEKKERING.
